DIAGNOSTIC COMPOSITION

Ernest C. Adams, Jr., Elkhart, Ind., assignor to Miles Laboratories, Inc., Elkhart, Ind., a corporation of Indiana

No Drawing. Filed Apr. 22, 1959, Ser. No. 807,993

8 Claims. (Cl. 195—103.5)

This invention relates to a new and improved diagnostic composition and is particularly concerned with a glucose indicator which is useful for the qualitative detection and quantitative determination of glucose in biological fluids, such as urine, and wherein the reagent composition is incorporated upon a bibulous carrier.

The detection of glucose in urine as well as the determination of its concentration therein is of great importance for diabetic patients who must control their diets so as to regulate their sugar intake and who must frequently be guided in this regard by a regular check on urine glucose. But beyond its usefulness in regular urine testing on known diabetics by both patients and physicians, this glucose indicator may also be used efficiently in routine urinalyses in hospitals and physicians' offices, in diabetes detection screening programs, in the differentiation of glucosuria from other melitarias, and the like.

Because early diagnosis and continued control are so important in diabetes, a urine-sugar test, to be of greatest value, must be conveniently rapid, simple enough for any patient to learn with ease, accurate enough to serve the clinician, and sensitive enough to reflect variations in the patient's condition. Moreover, the reagent composition must be adequately stable.

Procedures for the detection of sugar in urine are well known in clinical chemistry. One such procedure utilizes Benedict's copper reduction test, another employs a self-heating alkaline copper reduction test in tablet form (U.S. Patent No. 2,387,244), still another involves a test which depends solely on the action of enzymes (U.S. application No. 514,395, filed June 9, 1955, by Alfred H. Free and assigned to the assignee of the present invention). None of these procedures, however, has entirely satisfied the above-mentioned requirements.

I have now found a novel and highly useful glucose-detecting means which represents an important improvement and a fresh approach to the problem of determining glucose in various materials including body fluids, such as urine, by a technique that utilizes a diagnostic composition which is better than even the latest and most commonly used glucose tests.

Specifically, I have now found that a unique combination of a glucose oxidase system for determining glucose with a novel titanium potassium oxalate system for detecting hydrogen peroxide offers a superior means for testing biological fluids for their glucose contents.

A diagnostic composition according to the present invention comprises then as essential constituents glucose oxidase and titanium potassium oxalate (titanyl potassium oxalate— $TiO(COO.COOK)_2$).

The glucose oxidase (glucose aerodehydrogenase), as is well known, catalyzes the aerobic oxidation of glucose to produce gluconic acid (gluconolactone) and hydrogen peroxide as reaction products. The titanium potassium oxalate, in turn, reacts with the hydrogen peroxide formed in the above reaction to yield a titanium addition compound of a characteristic yellow color which is

5

10

2

immediately indicative of the glucose content of the fluid being tested. The latter reaction may be represented by the following equation:

The incorporation and use in this new glucose indicator of titanium potassium oxalate, which is commercially available, represents a substantial and significant advance in the art pertaining to glucose diagnostics. Glucose indicators presently on the market depend for the detection of hydrogen peroxide on complex oxidation-reduction reactions which occur only in the presence of enzymes (e.g. peroxidases) and involve the formation of intermediate compounds. The glucose indicator of the present invention, on the contrary, is based, as stated above, on a plain and straightforward chromogenic addition reaction of hydrogen peroxide with titanium potassium oxalate.

Titanium sulfate (titanyl sulfate— $TiOSO_4$) has in the past been used in analytical chemistry for detecting hydrogen peroxide (Eisenberg, Ind. Eng. Chem., Anal. Ed., 15, 327—1943). The usual method for detecting hydrogen peroxide with titanium sulfate is to suspend it in water and then use the supernatant liquid. However, it is not feasible to utilize titanium sulfate in accordance with the method just described or any other method in conjunction with a formulation which includes glucose oxidase for two reasons: first, a titanium sulfate solution is, due to the ready hydrolysis, and consequent decomposition, of titanium sulfate, extremely acidic and therefore destructive of glucose oxidase; secondly, with titanium sulfate thus not being highly soluble in water, it would not be possible to achieve in the impregnating mixture the high concentration thereof which is required as those who are versed in the art of preparing bibulous test strips will appreciate.

In contrast, titanium potassium oxalate is very soluble in water and gives upon dissolution therein the requisite neutral solution.

In place of the titanium potassium oxalate it is also possible, and therefore contemplated, to employ other equivalent, i.e. highly soluble and non-acidic, titanium oxalates such as titanium sodium oxalate, titanium ammonium oxalate, etc.

It is understood that such additives can be incorporated in the reagent composition as suitable protective agents, wetting agents and inert dyes to impart thereto a uniform background color.

Furthermore, it is important to include an appropriate buffer system to maintain a desired pH range in the presence of urine. Although the pH range may vary between 3.5 to 5.2, an especially preferred pH is 4.8. It must be borne in mind that if the diagnostic is too acidic, that is, the pH is less than about 3.5, the glucose oxidase would be destroyed, while at a pH substantially higher than 5.2, the development of a distinctive bright yellow color would be thwarted since the yellow color obtained on reacting titanium potassium oxalate with hydrogen peroxide is brighter with more acidic reaction media.

Although the test device itself may comprise the reagent composition in the form of a tablet, powder, or other embodiment, I prefer, to insure ease and simplicity of test procedure, to affix the reagent composition on bibulous base materials or carriers, such as strips or sticks of filter paper, by dissolving the component in a suitable solvent, impregnating the bibulous strips with the resulting solution and drying the impregnated test

70

strips. As will be obvious from the examples, it is very easy to prepare the instant glucose indicator due to its manifest simplicity.

The invention will now be illustrated in greater detail, but not limited, by the following examples:

EXAMPLE I

Preparation of impregnating solution

About 400 mg. of sodium alginate were dissolved in 20 ml. of water, and to this solution there was added a gelatin solution consisting of 400 mg. of gelatin in 10 ml. of water. Then, 4,000 mg. of titanium potassium oxalate were dissolved in 20 ml. of water, and this solution was mixed with the sodium alginate-gelatin solution. Next, 24 ml. of a pH 4.8 buffer solution (prepared by dissolving 32.6 g. of sodium citrate and 7.4 g. of citric acid, each per 100 ml. of water) were added with stirring. And lastly, a solution of 1,200 mg. of commercially available glucose oxidase (16,000 units per gram) in 10 ml. of water were likewise added, and the mixture was stirred well.

Preparation of reagent strip

Bibulous strips, such as filter paper cut into narrow strips with a water-impervious barrier of ethyl cellulose, one-half inch from the tip, were dipped into the impregnating solution so that through the process of submersion and capillary attraction the entire one-half inch of the strip up to the barrier was completely impregnated. These strips were then dried in a hot air oven at 100° C. for from about a few minutes to several hours. The test portion of these strips is of a buff color. Other porous or absorbing materials, such as small sticks of wood, etc., may likewise be used.

EXAMPLE II

About 20 ml. of water, 400 mg. of gelatin in 10 ml. of water, 4,000 mg. of titanium potassium oxalate in 20 ml. of water, 24 ml. of buffer solution (prepared as described in Example I) and 1,200 mg. of glucose oxidase (16,000 units per gram) in 10 ml. of water were mixed with stirring to give a uniform impregnating solution. Test strips were then prepared in accordance with the procedure recited in Example I.

EXAMPLE III

To an impregnating solution obtained as described in Example I there was added as an inert dye 1 mg. of FD&C Blue No. 1 in 0.2 ml. of water. For the preparation of the test strips the procedure given in Example I was followed.

Procedure of testing

In use, an impregnated strip made as described in any one of the above examples, is dipped into the liquid specimen to be tested. When contacted with urine containing glucose, a test strip will give a positive reaction in about one-half to one and one-half minutes evidenced by various shades of yellow color as follows:

With urine containing 1% or 2% glucose an intense bright yellow color develops in about one-half minute, while with urine containing 0.1% glucose the buff color of the impregnated strip changes to a faintly yellow color in about one minute. With urines containing 0.25% and 0.5% glucose the yellow colors which develop are of intermediate intensities, the urine having the greatest glucose content producing the brighter yellow. When dipped in urine containing no glucose, the strips undergo no color change. A simple color chart based on this phenomenon may be conveniently prepared for use in testing for urine glucose.

Test strips impregnated with any of the solutions described in the above examples are strikingly stable. For example, after exposure for 90 hours to a temperature of 50° C. and a relative humidity of 100% no loss in reactivity was perceptible. The impregnating solution has also been found to be unusually stable and may be left

standing without any deteriorative effect. I am not aware of any other diagnostic formulation with glucose oxidase that evidences such surprising stability.

In summary, this invention pertains to a diagnostic test for the detection of glucose in body fluids, and especially in urine, consisting of a bibulous strip or stick that has been impregnated with a composition comprising glucose oxidase and titanium potassium oxalate. The latter reacts with the hydrogen peroxide formed when glucose is oxidized in the presence of glucose oxidase to yield a yellow titanium addition compound.

What is claimed is:

1. A diagnostic composition for detecting glucose which comprises glucose oxidase and a titanium oxalate selected from the group consisting of titanium potassium oxalate, titanium ammonium oxalate and titanium sodium oxalate, said titanium oxalate being capable of reacting with hydrogen peroxide formed when glucose is aerobically oxidized in the presence of glucose oxidase to produce a yellow addition compound.
2. A diagnostic composition for detecting glucose according to claim 1 wherein said titanium oxalate is titanium potassium oxalate.
3. A diagnostic composition for detecting glucose which comprises glucose oxidase, a titanium oxalate selected from the group consisting of titanium potassium oxalate, titanium ammonium oxalate and titanium sodium oxalate and a buffer for maintaining the pH of said composition in the presence of urine at between 3.5 and 5.2.
4. A diagnostic composition for detecting glucose according to claim 3 wherein said titanium oxalate is titanium potassium oxalate.
5. A diagnostic composition for detecting glucose according to claim 3 wherein the pH is maintained at 4.8.
6. A diagnostic composition for detecting glucose which comprises glucose oxidase, titanium potassium oxalate capable of reacting with hydrogen peroxide formed when glucose is aerobically oxidized in the presence of glucose oxidase to produce a yellow addition compound, and a buffer for maintaining the pH of said composition in the presence of urine at 4.8.
7. A diagnostic composition for detecting glucose which comprises:

	Parts
45 Glucose oxidase	12.00
Titanium potassium oxalate	40.00
Sodium citrate (dihydrate)	78.24
Citric acid (anhydrous)	17.76
50 Sodium alginate	4.00
Gelatin	4.00
FD&C Blue No. 1	0.01

8. A test indicator for detecting glucose which comprises a bibulous material which contains therein the dried residue resulting from depositions on said material, followed by drying, of a liquid comprising glucose oxidase, titanium potassium oxalate capable of reacting with hydrogen peroxide formed when glucose is aerobically oxidized in the presence of glucose oxidase to produce a yellow addition compound and a buffer for maintaining the pH of said composition in the presence of urine at 4.8.
